United States Patent Office.

P. F. KESSLER AND JOHN CARLISLE, OF DAYTON, OHIO.

Letters Patent No. 78,377, dated May 26, 1868.

IMPROVEMENT IN STEAM-HEATERS.

The Schedule referred to in these Letters Patent and making part of the same.

TO ALL WHOM IT MAY CONCERN:

Be it known that we, P. F. KESSLER and JOHN CARLISLE, of Dayton, in the county of Montgomery, and in the State of Ohio, have invented certain new and useful Improvements in Steam-Radiators; and do hereby declare that the following is a full, clear, and exact description thereof, reference being had to the accompanying drawings, and the letters of reference marked thereon.

In the annexed drawings making a part of this specification—

Figure 1 represents a longitudinal section.

Figure 2 represents a side elevation, with the outer jacket taken off, and broken lines at the bottom showing the interior pipes.

A represents a flat, oblong-shaped metallic shell, within which is a series of short pipes or tubes, *b b b*, placed at suitable distances from each other, and separated by a series of partition-plates, *a a a*. These pipes and partitions form parallel steam-channels, as seen in fig. 1.

The shell A may be made of any desired dimensions, provided with one or more series of parallel circular openings or holes through both sides, corresponding with the pipes *b*, and to the edges of which the circular pipes *b* are secured, thus forming a series of holes through the shell A.

At one end of the shell A, through both of its sides, is a hole of suitable size, ordinarily two inches in diameter. Screw-threads are cut in the metal of the sides of the shell, forming female screws, and into which may be screwed a metallic nipple, B, with screw-threads on both ends. Said nipple B is ordinarily made of wrought iron, and hollow. By means of the nipple B, two or more of the shells A may be joined together, as may be required, with tubular passages from one to the other through the nipple B.

We insert a steam-pipe, C, through the hole in the outside of the shell A, and through the tube formed by the nipple B, and secure it and close the outside hole in the shell by means of a bushing, or a collar provided with screw-threads on said pipe.

The end of the pipe C which is inserted is closed, but is provided with holes at its side, corresponding with and leading directly into one of the steam-channels of each shell, by which means the steam is compelled to pass first up one of the steam-channels of each shell, and forces the air in front of it out of and into the other channels. Thus the shells A are simultaneously and equally heated in all their parts.

It will be seen that the steam is passed up the channels, as indicated by the arrows, and passes out (forcing the air ahead of it) the outlet *d* or outlet *E*, as may be most convenient.

D represents a metallic plate adjusted between each of two parallel shells A, so cut and punched as to make numerous tongues or projections at right angles to either side of said plate. A similar metallic case, E, with projections inwardly only, embraces and encloses each series of shells A and plates D, and is secured in any manner desired to the inner side of a flue or oven, into which the radiator, as a whole, is adjusted vertically.

The plates D and case E, with their tongues or projections, are placed sufficiently near the shells A to break the upward currents of air, and thereby cause more particles to impinge the heated shells, by which means heat is more readily and completely disseminated.

Having thus fully described our invention, what we claim as new, and desire to secure by Letters Patent, is—

1. The metallic plates D and the case E, in combination with the shells A in radiators, as and for the purpose set forth.

2. The arrangement of the shells A A, pipes *b b*, partitions *a a*, nipples B B, steam-pipe C, and case E, when the several parts are constructed and operate substantially as and for the purposes set forth.

In testimony that we claim the foregoing, we have hereunto set our hands, this 10th day of December, 1867.

P. F. KESSLER,
JOHN CARLISLE.
